Primary Examiner — T. Chase Nelson*Assistant Examiner* — Mark Cavanna(74) *Attorney, Agent, or Firm* — Whyte Hirschboeck Dudek S.C.; James A. Joyce(57) **CLAIM**

The ornamental design for an implant tracking device, as shown and described.

DESCRIPTION

FIG. 1 is a perspective view of an implant tracking device showing my new design;

FIG. 2 is a front elevation view thereof;

FIG. 3 is a top plan view thereof;

FIG. 4 is a side elevation view thereof;

FIG. 5 is a back elevation view thereof; and,

FIG. 6 is a bottom plan view thereof.

The broken lines are included for the purpose of illustrating portions of the implant tracking device that form no part of the claimed design.
